UNITED STATES PATENT OFFICE.

GUSTAVO NICHOLSON, OF AQUINO, PARAGUAY.

FIREARM.

Application filed July 11, 1925. Serial No. 43,026.

This invention relates to new and useful improvements in fire-arms, and particularly to revolvers.

One object of the invention is to provide a fire-arm wherein the hammer is properly protected from accidental discharging movement, when cocked.

Another object is to provide a fire-arm wherein the mechanism is securely housed against entrance of dust.

Another object is to improve and simplify the mechanism whereby the fire-arm may be quickly and easily opened for discharging empty shells, and for reloading.

A further object is to provide a fire-arm frame which is strong and durable, and wherein the barrel is properly and effectively supported, against displacement or contortion, while at the same time permitting easy reloading.

A still further object is to provide a novel and improved construction of mechanism for revolving the cartridge cylinder.

Other objects and advantages will be apparent from the following description when taken in connection with the accompanying drawings.

In the drawings:

Figure 1 is a side elevation of a revolver made in accordance with the present invention.

Figure 2 is a vertical longitudinal central sectional view through the revolver, showing the parts in normal position.

Figure 3 is a view similar to Figure 2, but showing the parts when cocked by hand.

Figure 4 is a sectional view, similar to that of Figure 2, but showing the position of the parts when the trigger has been pulled, and the revolver is ready to be discharged.

Figure 5 is a vertical transverse sectional view on the line 5—5 of Figure 2.

Figure 6 is a sectional view, similar to that of Figure 5, but showing the cylinder carrying portion of the chamber as swung toward one side, to permit the extraction of the empty shells, and reloading of the cylinder.

Figure 7 is a horizontal sectional view on the line 7—7 of Figure 2, looking downwardly.

Figure 8 is a horizontal longitudinal sectional view on the line 8—8 of Figure 2, looking downwardly.

Figure 9 is a horizontal sectional view on the line 9—9 of Figure 2, looking upwardly.

Figure 10 is a horizontal detail sectional view on the line 10—10 of Figure 2.

Referring particularly to the accompanying drawings, 10 represents the barrel of the revolver, which has, on its rear end, the L-shaped frame portion 11, and on the lower end of a vertical portion of the said frame 11 there is formed a hook-like portion 12, to which reference will be made later herein. On the rear end of the horizontal portion of the frame 11 there is formed a rearwardly extending rod or bolt 13, the rear end of which is externally threaded. The pistol-grip is shown at 14, and on the upper end of said grip there is formed the frame 15, said frame having the upwardly extending portion 16. Formed longitudinally in this portion 16 are the bores 17 and 18, in the former of which is received the said bolt or rod 13, nuts 19 and 20, the latter being provided with notches for the reception of the blade of a screwdriver. On this rod or bolt 13, the frame 11, and barrel, are adapted to be swung, for the purpose of moving the cylinder for the extraction of empty shells, and reloading the cylinder, as will appear later herein. Extending forwardly from the lower portion of the frame 16, is an arm 21, and formed longitudinally in this arm is a bore 22, the outer end of which is countersunk, at 23, while the upper face of the arm is formed with an elongated opening 24 for the reception of the hook-like portion 12, said opening extending through the side of the arm and having the rearwardly extending lug 25, for engagement within said hook. Slidably disposed in the bore 22 is a bolt 26, having a cut out portion 27, in its upper side, and a V-shaped shoulder 28 at the rear end of said cut out portion for engagement in a correspondingly formed notch 29 in the rear face of the hook 12, whereby to hold the arm 21 in locked, but releasable engagement with the vertical portion of the L-shaped frame 11. In the inner end of the bore 22, and bearing against the inner end

80
85
90
95
100

wall thereof, and against the inner end of the bolt 26, is a coil spring 30, which urges the bolt outwardly so that the shoulder 28 engages in the notch 29. In the lower side 5 of the bolt 26 there is formed an elongated recess 31, in which is disposed the transverse pin 32, whereby to limit the sliding movement of the bolt. In the bore 18 is disposed the firing pin 33, said pin having its forward end reduced in diameter at 34, to provide the shoulder 35, against which the rear end of the coil spring 36 abuts, the other end of the spring bearing against the shoulder 37, at the forward end of the bore, and 10 through which said reduced portion 34 slides. In the lower side of the firing pin there is formed an elongated recess 38 in which is disposed the transverse pin 39, for limiting the sliding movement of the firing pin. In the forward end of the vertical extension 16 there is formed the longitudinal recess 40 in which is disposed the cylindrical member 41, which is adapted to rotate the cylinder 42 of the revolver.

25 Disposed longitudinally through the vertical portion of the L-shaped frame 11, below the barrel, is a rod 43, the inner end of which is coupled to a rod 44 which extends longitudinally through the center of the cylinder 42. The other end of the rod 44 is provided with a flat head 45, the periphery of which is formed with the series of recesses 46, resulting in the intermediate projections or fingers 47, said recesses receiving the bodies of the cartridges 48, below the flanges thereof, and whereby, upon longitudinal movement of the said rods 43 and 44, said head 45 will eject the shells of the cartridges from the bores of the cylinder 42. 30 This is accomplished by pressing inwardly on the outer end of the outer rod 43, which protrudes beyond the vertical portion of the frame 11, where it is provided with a milled or knurled head 49. Formed on the frame 45 15, between the arm 21 and the grip 14, is the trigger guard 50, and formed in the rear end of the arm 21, and opening through the upper side of the arm, is an elongated recess 51, and slidable in this recess is a small 50 block 52, the upper end of which is arranged to engage successively in the notches or recesses 53 in the peripheral face of the cylinder 42. In the recess 51, below the block 52, and arranged to resiliently urge the block 55 upwardly, is a coil spring 54. Pivotal 55 supported on the block 52 is an L-shaped member 55, a spring 56 being arranged between the member 55 and the block whereby to urge the member in the direction of 60 the trigger 57, which trigger is pivotally mounted in the frame 15, above the guard 50, and has its fingerpiece 58 disposed within the guard, as seen in the drawings. Formed on the forward side of the trigger 57, and 65 arranged to engage the horizontal portion

55 of member 55, is a nose 59, the lower face of this horizontal portion of the member 55 being beveled at 60, whereby to permit the said nose to readily pass the said portion, when moving upwardly, and to engage and depress the member, when moving downwardly. In the rear of the upper portion of the frame 15 there is formed a vertical opening 61, and pivoted within the frame, and movable in said opening, is the hammer 62, the pivotal portion 63, of which is in the form of a disk, and has the peripheral notches 64, 65, and 66. Formed on the upper portion of trigger is a projection 67, and pivoted at one end to this projection is a link 68, said link including the parallel side bars 69, connected at their ends by the transverse pins 70 and 71 and the intermediate wider and flat portion 72. The pin 70 is engaged through an opening in the projection 67, and forms the pivotal connection between the link and the trigger. The other pin 71 is engaged in the notch 65, of the pivotal portion of the hammer 62. Mounted on the forward wall of the interior of the grip 14 is a vertically arranged member 73, having the central longitudinal groove 74, in which is received the rib 75 of the slidable hollow member 76. A stop lug 77 is formed on the upper end of the member 73, to limit the upward movement of the member 76. Removably secured in the bottom of the grip 14, and extending upwardly into the hollow member 76, is a pin or post 78, a coil spring 79 being arranged within the member 76, and normally urging said member upwardly. Pivotal connected to one side of the slidable member 76 is an upwardly extending arm 80, the upper end of which is formed with a head 81 engaged in the notch 66 of the hammer. In the extension 16, below the recess 40, there is formed a longitudinal channel 82, and slidable in this channel is the block 83. On the upper side of the forward end of the block 83 there is formed a lug 84 which engages in the S-shaped groove 85, of the cylindrical member 41 for rotating the latter. Removably secured to the side of the grip 14, and the extension 16, of the frame 15, is a plate 86, and formed on the inner face of this plate is a lug 87, having a semicircular recess which receives the peripherally grooved rear end of the member 41. A similar lug 88 is formed on the extension 16 for engagement in the groove of the member 41, at the other side thereof, whereby said member is held against any longitudinal movement, while being permitted free rotation within the recess 40. In the lower side of 125 the forward end of the slidable block 83 there is formed a notch 89, and within this notch is disposed the upper end of the projection 67, of the trigger, said lug being arranged to move the block 83 longitudinally 129

within the channel 82. The rear end of the channel 82 is slightly deeper than the main portion thereof, as shown at 90, and disposed for slidable movement in this deeper portion 90 is the pawl 91, said pawl being slidable, also, in the groove or recess 92, formed in the lower side of the block 83, and having an upwardly extending lug 93 for engagement with the end walls of said recess 92, to limit the movement of the pawl, and whereby said pawl is arranged to be moved by the block. A coil spring 94 urges the pawl into the notch 64, of the hammer. Below the portion 90 of the channel 82 there is formed a tapered projection 95, with which is arranged to engage the beveled shoulder 96, of the link 68, for a purpose which will presently be explained. Formed vertically through the rear end of the block 83 is an opening 97, and disposed within this opening is the vertical arm of the L-shaped safety latch 98, the horizontal arm of which is arranged to lie, at times, forwardly of the hammer, whereby to prevent contact of the latter with the rear end of the firing pin. In the upper side of the trigger there is formed a recess 99, and disposed within this recess, and bearing with its upper end against the link 68, is a coil spring 100, said spring serving to urge the link upwardly to engage its rear pin 71 in the notch 66.

In the upper side of the member 41 there is formed a longitudinal groove, the rear portion of which is deeper than the main portion thereof, to provide the shoulder 102, the said groove being represented by the numeral 101. Slidable in this groove is the pawl 103, the forward end of which is provided with a beveled nose 104 for engagement with the ratchet teeth 105, formed on the head 45, in surrounding relation to the center thereof. The pawl has a downwardly extending lug 106 which plays in the groove between the shoulder 102 and the rear end of the groove, a coil spring 107 being arranged between the rear end of the pawl and the rear end wall of the groove, for the purpose of urging the pawl into engagement with the said ratchet teeth 105.

In the upper arm of the frame 11 there is formed a longitudinal slot 108, and pivotally mounted in this slot is a spring pressed detent 109, one end of which is formed with a lug 110 for engagement with the rear end of the cylinder 42, for holding the latter against displacement, when the frame 11 is swung on the rod 13. Encircling the rod 44, within the central bore of the cylinder 42, is a coil spring 44', one end of which bears against shoulder formed in the rear end of the central bore of the cylinder 42, while the other end bears against the coupling sleeve between the rods, whereby upon rearward movement of the rods, when pressure is ap-

plied to the head 49, the head 45 will eject the empty shells from the cylinder, and the spring 44 be compressed. Upon release of the rods, the spring will expand and restore the parts to normal position so that the head 45 will lie beneath the flanges of the cartridges. 50

The side faces of the hammer 62 are knurled to provide an efficient grip for cocking the same by hand.

When the parts are in their normal position, as shown in Figure 2, and the cylinder 42 properly loaded with cartridges, upon pulling the trigger rearwardly the nose 59, of the trigger will engage on the nose 55, of the member 55, which causes the downward movement of the block 52, whereby to release its upper end from a notch of the cylinder 42. Simultaneously with this operation of the member 55, the projection 67 moves the block 83 forwardly, in the direction of the cylinder 42, and at the same time draws the link 68 forwardly. As the block 83 moves forwardly its lug 84, engaging in the S-shaped groove 85, causes the member 41 to be partially rotated, with the result that the pawl 103 engages with a tooth of the head 45, and rotates the cylinder 42 one step. As the trigger swings forwardly the link 68 operates on the hammer 62, through the engagement of the pin 71 in the notch 66, of the pivotal portion of the hammer, to swing the hammer rearwardly. This rock-

100
105
110
115

...ing the hammer forwardly. This rock-
ing movement of the hammer pushes the
member 76 downwardly, through the me-
dium of the arm 80, whereby to compress the
spring 79. When the hammer has been
swung to a certain degree the pawl 91 is
urged into the notch 64, by the spring 94,
whereby the hammer is held in cocked posi-
tion. The block 83 is carried forwardly by
the trigger until the rear end wall of its re-
cess 92 engages with the lug 93, of the pawl
91, when said pawl is moved forwardly out
of the notch 64, thus releasing the hammer
so that the expansive force of the spring 79
will, through the medium of the arm 80,
urge the hammer forwardly into striking
engagement with the firing pin 33, which
firing pin is driven forwardly against the

cartridge in the cylinder 42. This compresses the spring 36, so that said spring will cause the firing pin to recoil and force the hammer backwardly to permit the pawl 103 to again engage a tooth 105, ready for the next turning action on the cylinder 42. The spring 100 causes the restoration of the trigger to normal position, which at the same time urges the link 68 upwardly and reengages its pin 71 within the notch 65. Simultaneously with the release of the pawl 91 from the notch 64, the shoulder 96, of the link 68 engages and rides on the tapered projection 95, causing the link to be depressed so as to disengage its pin 71 from

the notch 65. As the trigger moves toward the normal position its projection 59 trips the member 52, so as to swing the same out of the way, the spring 54 immediately restoring the said member into normal position with its nose beneath the projection 59, ready for the next operation, when the trigger is again pressed back. It will be noted that when the block 83 moves forwardly, 10 the safety latch 98 is rocked so that its horizontal arm swings downwardly out of the path of the hammer, whereby the hammer may properly advance to strike the firing pin. When the parts are restored to normal 15 position, the block 83, by its engagement with the latch 98 rocks said latch so as to dispose its horizontal arm in the path of the hammer, whereby to hold the hammer at a safe distance rearwardly of the rear end 20 of the firing pin.

When cocked by hand the parts assume the position shown in Figure 3, and upon a slight rearward pull on the trigger, the pawl 91 will be released from the notch 64, 25 and the pin 71 released from the notch 65, thus permitting the hammer to be thrown forwardly into striking engagement with the firing pin, under the influence of the spring 79.

When it is desired to extract the empty shells, the bolt 26 is pushed inwardly, whereby to release the shoulder 28 from the notch 29, and thus permit the barrel, and the frame 11, to be swung sidewise. The 35 rod 43 is then pushed inwardly to cause the head 45 to discharge the shells from the cylinder 42. Upon release of the rod or bolt 43 the spring 44' returns the ejector head 45 to its normal position against the rear end of the cylinder 42. The detent 108 holds the cylinder 42 from movement from the rod 44, when the fire arm is opened, as above explained, but if it is desired to remove the cylinder from the rod, 40 the spring pressed end of the detent is depressed, whereby to disengage its lug 110 from the cylinder.

What is claimed is:

1. A firearm including a frame, a barrel, 50 a cylinder, a hammer, and a trigger, means operable by the trigger, upon initial movement thereof, for cocking the hammer, trigger actuated means for rotating the cylinder upon partial movement thereof, 55 means on the rotating means for engagement with the hammer when the latter is in cocked position to hold the same in such position until the cylinder has been rotated, and means operable by the trigger, upon final movement thereof for completing the movement of the rotating means whereby to release the hammer holding means.

2. A firearm including a frame, a barrel, 60 a cylinder, a hammer, and a trigger, means for rotating the cylinder, means operable

by the trigger for actuating said rotating means, means carried by the last-named means for engagement with the hammer to hold the latter in cocked position and releasable upon the completion of the cylinder rotating operation, means carried by the trigger and engaged with the hammer for cocking the latter, upon initial movement of the former, and a hammer impelling means operatively connected with the hammer and actuated into set position upon cocking movement of the hammer.

3. A firearm including a hammer, a trigger, and a cylinder, a rotatable means for turning the cylinder a single step, a trigger actuated means operably engaged with the rotatable means for rotating the same, a detent carried by the trigger actuated means and urged into engagement with the hammer, means connected with the trigger and engaged with the hammer for cocking the latter upon initial movement of the former, spring means for impelling the hammer, means operable by the hammer, upon cocking thereof, for compressing the spring means, said detent being arranged to be withdrawn from engagement with the hammer upon final movement of the trigger, and means for releasing the trigger carried means from the hammer upon final movement of the trigger.

4. A firearm including a trigger, a hammer, a cylinder, and a compressible hammer impelling means, a slidable member operatively engaged by the trigger, a pawl for engagement with the hammer, means on the pawl for engagement by the slidable member whereby to move the pawl into and out of engagement with the hammer, means carried by the trigger and urged into engagement with the hammer for cocking the latter, means operable by the hammer, upon cocking movement of the latter, for compressing the impelling means, and means operable by the slidable member for rotating the cylinder a single step.

5. A firearm including a rotatable cylinder, a hammer, and a trigger, a rotatable slotted member, a resiliently urged means carried by the slotted member for engagement with the cylinder for rotation thereof, a slidable member operatively connected with the trigger for movement thereby, means on the slidable member for rotating the rotatable slotted member, means normally urged into engagement with the cylinder for holding the latter against rotation, and means operable by the trigger for releasing the cylinder holding means.

6. A firearm including a rotatable cylinder, a hammer, and a trigger, the hammer having a pivotal portion provided with notches, means movably carried by the trigger and engaged in one of said notches for cocking the hammer, a slidable member

actuated by the trigger and having spring pressed means engaging in another notch of the hammer when the latter is in cocked position for holding the latter in such position, a cylinder rotating means operable by the slideable member, said hammer holding means being releasable from the hammer by the slideable member upon completion of the cylinder rotating operation thereof, a hammer impelling spring, and means engaged with the spring and with the hammer whereby to compress said spring upon cocking movement of the hammer.

In testimony whereof, I affix my signature.

GUSTAVO NICHOLSON
